BOX OR CARTON

Henry Levine, Philadelphia, Pa.

Application June 2, 1933, Serial No. 673,964
In Denmark March 7, 1933

10 Claims. (Cl. 229—29)

This invention relates generally to cartons or containers and more particularly to an improved construction of cellular carton of the type adapted to receive eggs or other fragile articles requiring protection in the handling thereof.

Among the principal objects of the present invention is to provide a cellular carton wherein the longitudinally and transversely extending division walls thereof are formed from a single blank and wherein means are provided for effectively interlocking said division walls to afford a substantially rigid and self-sustaining structure; to provide a cellular carton wherein the longitudinal and transverse walls are so related to each other that the assembly thereof into the form of a complete carton is effected expeditiously by a simple manual operation and without necessitating the use of any special tools or assembling devices; to provide in a cellular carton a separate, readily insertable means which functions not only to interlock the longitudinal and transverse partition walls but which also serves to support the bottom wall of the carton against collapse, the said bottom wall being suspended from said readily insertable means instead of from the transverse partition walls as has heretofore been the general practice in cellular cartons of the type with which this invention is concerned; to provide an improved construction of top lid or closure for the cellular carton, said lid or closure being so designed as to enable it to be quickly detachably secured to the carton; and to generally improve the construction of the carton so that when eggs or similar articles are respectively received within the cellular compartments thereof they are so supported that the upper portions thereof are sufficiently exposed to facilitate their easy removal from the carton.

Other objects of the invention will be apparent more fully hereinafter.

The invention consists substantially in the combination, construction, location and relative arrangement of parts, all as will appear more fully hereinafter, as shown in the accompanying drawing and as finally pointed out in the appended claims.

In the accompanying drawing, which illustrates certain preferred constructions of cellular cartons embodying the features of the present invention:—

Figure 1 is a view of the blank from which a box constructed in accordance with the present invention is formed;

Figure 2 is an end elevational view of the box in its expanded form;

Figure 3 is a top view of the box, a portion of the integral lid thereof being cut away to expose the interior of the box;

Figure 4 is a perspective view of the locking member employed for interlocking the longitudinal and transverse division walls of the box;

Figure 5 is a view of a blank from which a modified form of the box is formed;

Figure 6 is a view of the blank from which the top cover or lid of the modified box is formed;

Figure 7 is a side elevational view of the box formed from the blanks shown in Figures 5 and 6; and

Figure 8 is an end elevational view of the box shown in Figure 7.

The box or carton which is constructed in accordance with the present invention is preferably produced from a paper stock such as chip board having the inherent capacity of resiliency and of bending along predetermined lines such as are produced by a scoring operation. Such a material, which will meet the requirements of the present invention, is inexpensive and well-known at the present time for the manufacture of cellular boxes or cartons.

Referring to the drawing and more particularly to Figures 1 to 4, inclusive, the blank 10 of which the carton is formed is in the form of a single sheet of material, this sheet being of substantially rectangular form and being suitably scored along the parallel lines *a*, *b*, *c*, *d*, *e*, *f*, *g*, *h* and *i* to provide a plurality of foldable sections or strips 11, 12, 13, 14, 15, 16, 17, 18, 19 and 20. The intermediate section 19 is suitably stamped to provide a series of partially cut out partition members 21, each of these partition members being integrally anchored to the opposite sections 18 and 20 by means of triangular connecting strips or tongues 22. The free ends of each partition member 21 are so cut along the line 23 to provide a pair of laterally spaced substantially triangular projections 24—24, at the same time that each partition member is provided with an upwardly extending projection 25. These partition members 21 are adapted to be swung into planes substantially paralleling each other and extending at right angles to the flat plane of the blank 10.

In the carton constructed of the blank shown in Figure 1, the lid or top closure member therefor is formed as an integral part of the blank, this lid being the section 12 of the blank. It

will be observed that the sections 15 and 16 conjointly form the longitudinally extending central partition of the carton, these sections being adapted to be folded along the scored lines *e* to provide a longitudinally extending central partition of substantially inverted V-shape (see more particularly Figure 2). This central partition is adapted to be interlocked with the several transverse partition members 21 and to that end the sections 15 and 16 are commonly slotted, as at 26, to provide a plurality of longitudinally spaced notches in the ridge of the longitudinally extending partition member, these notches 26 being adapted to respectively receive the bottom edges of the transverse partition members 21.

Each of the transverse partition members 21 is provided with an opening 27 therein, these openings being so located in the several members 21 that when the latter are properly engaged with the longitudinally extending partition member, the common axis of the aligned openings 27 is substantially coincident with the ridge of the longitudinally extending partition member.

When the blank 10 is expanded into the shape of the box shown in Figures 2 and 3, it will be observed that the sections 13 and 18 constitute the opposite side walls thereof, the sections 14 and 17 constitute the inwardly and downwardly inclined portions of the bottom wall, and the sections 15 and 16 constitute the upwardly inclined portions of the bottom wall. The strip 20 is adapted to be glued or otherwise secured to the inner surface of the side wall 13, while the section 12 constitutes the lid of the carton, this section being adapted to rest upon the upper edges of the transverse partition members 21. The end section 11 of the blank constitutes the securing flap which is adapted to be bent downwardly along the scored line *a* for connection with the side wall 18 in the manner to be hereinafter described. In this connection, it will be observed that the outer or free edge of the section 11 is provided with a plurality of longitudinally spaced tongues 28. Reverting again to the blank shown in Figure 1, it will be observed that the transverse partition members 21 in that edge thereof which is coincident with the scoring line *h* are respectively provided with curved incisions 29, it being noted that when the blank is expanded into the form of the completed box, these incisions 29 provide spaces 30 of substantially semi-circular form between the side edges of the transverse partition members and the outer wall 18 of the box, these semi-circular spaces being respectively located immediately beneath the triangular connecting strips 22.

In order to effect desired and necessary interlocking relation between transverse partition members 21 and the longitudinally extending partition member formed by the sections 15 and 16, a separately insertable locking strip 30 is employed, this strip being shown most clearly in Figure 4 wherein it will be observed that it consists merely of a relatively narrow strip folded upon itself, the longitudinally extending edges 31 of the strip being preferably spaced from one another. In cross-section this strip is thus of substantially V-shape. This strip is projected through the aligned openings 27 of the transverse partition members with the ridge 32 thereof nested within the ridge formed by the members 15 and 16, the free edges 31 of the locking strip being respectively in engagement with the bottom edges of the opening 27 in the

transverse partition members 21. The locking strip 30 thus serves not only to effect a positive interlock between the transverse partition members 21 and the longitudinal partition but also as a support from which the bottom sections 15 and 16 of the carton are suspended.

With reference to the securing flap 11 of the lid, it will be observed that the tongues 28 thereof are respectively provided with freely projecting portions 33 extending longitudinally of the carton and in such direction that said portions 33 thereof are adapted to be respectively projected into the spaces 33^a formed between the side edges of the transverse partition members 21 and the side wall 18 of the box. The tongues 28 are thus frictionally engaged between side wall 18 of the box and the proximate edges of the transverse partition members at the same time that they are prevented from being vertically disengaged from the box by the triangular supporting strips 22.

In Figures 5 to 8, inclusive, a modified form of the box is illustrated, it being observed, however, that, in this modified form of box the transverse partition members are interlocked with the longitudinally extending central partition member by means of a separately insertable locking strip exactly as that employed in connection with the box previously described. The modified form of box differs from that previously described in the following respects. The blank 34 of which it is constructed does not include any lid section but instead includes merely the sections 35, 36, 37, 38, 39, 40, 41 and 42 which respectively correspond to the sections 13 to 20 of Figure 1. The lid section of the box is formed of a separate blank 43 shown in Figure 6, this blank 43 being provided with scoring lines *j* and *k* which divide the blanks into the sections 44, 45 and 46, the intermediate section 45 constituting the lid proper and the opposed sections 44 and 46 constituting the securing flaps by which the lid is secured to the carton proper. It will be observed that these securing flaps 44 and 46 are respectively identical with the securing flap 11 of Figure 1 both in structure and in operation.

The transverse partition members 47 of the blank 34 differ somewhat from the corresponding partition members 21 of the blank 10. In the first place, it will be noted that the curved incisions 48 are provided in each side edge of the partition member. Also, it will be observed that the opposite side edges of the transverse partition members 41 are tapered inwardly along the lines 49—49 in consequence of which there is provided as integral parts of the sections 40 and 42, longitudinally spaced acute angle projections 50. These relatively sharp-pointed projections 50 project upwardly in the plane of the opposite side walls of the carton when expanded into shape and above the upper edges thereof to such extent that they serve as guiding elements for the securing flaps of the lid 43 during the operation of securing the latter in position. In addition, as appears most clearly in Figure 7, these pointed projections 50, particularly when combined with the arcuately shaped portions 51 are ideally adapted for ornamental purposes inasmuch as they represent the head of a chick projecting upwardly from the upper edges of the side walls of the carton. To increase the effectiveness of this chick head design, the upwardly extending projections 50 and 51 may be colored or otherwise configured.

to conform with other suitable designs provided in the side walls of the carton.

A carton constructed in accordance with the principles of the present invention has the distinct advantage of being exceedingly easy to assemble, one hand being held below the box, while the other hand is employed to position the transverse partition walls in vertically parallel relation whereby to cause the bottom edges of said transverse walls to be respectively seated within the notches or slots 26 provided in the ridge of the longitudinally extending partition. When the side walls of the box are then compressed together, the natural result is to seat the transverse partition walls further into the notches 26 so as to present the ridge of the members 15 and 15 above the bottom edges of the aligned openings 27. The member 30 may then be slipped readily into position to permanently lock the box in expanded form.

In the form of box shown in Figures 5 to 8, inclusive, the lid may be removed entirely by shifting the same longitudinally of the box to effect the disengagement of all of the tongues 28^a from their respective sockets 48^a. Should it not be desired to remove the lid entirely, one or the other edges thereof may be disengaged from the carton while the opposite edge remains engaged therewith, the lid thus operating exactly in the manner of the lid of the box shown in Figures 1 to 3, inclusive. In other words, the lid may be swung upwardly about either of the scoring lines *j* or *k* exactly in the manner of a hinged lid.

A further and important advantage of the carton, constructed as hereinbefore described and as shown in the accompanying drawing resides in the fact that when the carton is to be shipped or stored and the conservation of space becomes an important factor, it may be compressed into substantially flat shape even though the anchoring strip (20 of Figure 1 and 42 of Figure 5) is glued or otherwise permanently secured to one wall of the carton, the compressing of the carton being effected along the scoring lines *c* and *g* of the carton shown in Figure 2 and along the scoring lines *l* and *m* of the carton shown in Figure 8. Of course, the compressing may be effected along other score lines as desired, it being understood, of course, that in all such instances where the carton is to be shipped or stored in compressed condition, the transverse partition walls are disengaged from the longitudinally extending partition and lie in a substantially flat plane.

It will be understood, of course, that the invention is susceptible of various changes and modifications without departing from the real spirit or general principles thereof and it is accordingly intended to claim the same broadly, as well as specifically, as indicated in the appended claims.

What is claimed as new and useful is:—

1. In a carton of the character described, a single sheet of material which is longitudinally scored to provide a plurality of longitudinally extending sections adapted to constitute the side and bottom walls of a carton when the blank is folded along said scored lines, one of said sections being slotted to provide a plurality of partition members which are adapted to be swung into vertically disposed substantially parallel relation for interlocking engagement with a longitudinally extending partition formed in
- of said longitudinally extending partition being said bottom wall of the carton, the upper edge provided with longitudinally spaced slots for respectively receiving the bottom portions of said transverse partitions, said transverse partitions being respectively provided with aligned apertures the common axis of which is substantially coincident with the upper edge of said longitudinally extending partition, and a locking strip extending longitudinally of the carton and interposed between the upper edge of said longitudinally extending partition and the bottom edges of said apertures whereby to maintain the transverse partitions interlocked with the longitudinally extending partition. 15
2. In a carton of the character described, a single sheet of material which is longitudinally scored to provide a plurality of longitudinally extending sections adapted to constitute the side and bottom walls of a carton when the blank is folded along said scored lines, one of said sections being slotted to provide a plurality of partition members which are adapted to be swung into vertically disposed substantially parallel relation for interlocking engagement 25 with a longitudinally extending partition formed in said bottom wall of the carton, the upper edge of said longitudinally extending partition being provided with longitudinally spaced slots for respectively receiving the bottom portions of 30 said transverse partitions, said transverse partitions being respectively provided with aligned apertures the common axis of which is substantially coincident with the upper edge of said longitudinally extending partition, and a locking 35 strip extending longitudinally of the carton and interposed between the upper edge of said longitudinally extending partition and the bottom edges of said apertures whereby to maintain the transverse partitions interlocked with the longitudinally extending partition, said locking means being supported by said transverse partitions and being in turn operative to support the bottom wall against downward collapse. 40
  3. A carton made of a single blank folded and glued to produce a shell having continuously extending side and bottom walls, the bottom wall being centrally folded to provide a longitudinally extending central partition member, the upper ridge of said partition member being provided with a plurality of longitudinally spaced slots therein, and transverse partitions integrally secured to the opposite side walls of the carton and adapted to be swung into substantially vertical positions for respective reception within 50 the slots aforesaid, said transverse partitions being respectively provided with longitudinally aligned apertures the bottom edges of which respectively lie below the upper edge of said central partition member, and means extending 55 longitudinally through said apertures and beneath the ridge of said longitudinal partition member for interlocking the transverse partitions to said longitudinal partition member. 60
  4. A carton made of a single blank folded and secured together to produce longitudinally extending tube, said blank being longitudinally scored to permit the walls of said tube to be bent into the form of a carton having side and bottom walls, the upper section of said tube being slotted to provide a plurality of longitudinally spaced partition members which are adapted to be swung into vertically disposed substantially parallel relation for interlocking engagement 70 with the bottom of the carton, and sep- 75

arable means extending longitudinally of the carton for interlocking said transverse partitions to said bottom wall, said means being longitudinally inserted into locking position.

- 5 5. A cell carton comprising top, bottom and side sections and a series of transverse partition members all formed from a single piece of material, the bottom section being longitudinally scored substantially midway between said side sections and bent along said score to provide an upstanding longitudinally extending partition member with which said transverse partition members are adapted to interlock, and separate means extending longitudinally of the box and supported by said transverse partitions for maintaining said folded bottom in raised position and in interlocked relation to said transverse partition members.
- 10 6. A carton made of a single blank adapted to be folded and secured together to produce a shell the bottom and side walls of which are of W-shape in vertical cross-section, a plurality of transverse members integrally secured at opposite upper corners thereof to the opposite upper edges of the side walls of the carton, said transverse partition being adapted to be swung into vertically disposed substantially parallel relation for interlocking engagement with the longitudinally extending intermediate section of the carton, the side edges of said transverse partitions being so cut as to provide spaces between the upper portions thereof and the proximate side walls of the carton, and a separable lid for the carton, said lid being provided with depending flanges extending along opposite longitudinal edges thereof, said flanges being each provided with a plurality of tongues adapted respectively for reception within the spaces aforesaid whereby to detachably secure said lid to said carton.
- 15 7. In a carton of the character defined in claim 6 wherein the side edges of the transverse partition members are so cut with respect to the side wall sections of the carton as to provide along the upper edges of the latter a plurality of longitudinally spaced raised projections, each of said projections lying substantially in the plane of their associated side wall.
- 20 8. In a carton of the character described, a single blank scored and slitted to provide a plurality of sections respectively constituting side and bottom walls of the carton and a plurality of transverse partitions spaced longitudinally in the length thereof, the side edges of said transverse partitions being so fashioned with relation to the opposite side walls thereof as to pro-

vide along the upper edges of said walls a plurality of upwardly extending projections and at the same time forming spaces between the inner surfaces of said side walls and the upper portions of the proximate edges of the transverse partitions, and a lid for said carton, at least one edge of said lid being provided with a depending flange having tongues respectively adapted to be accommodated within said spaces, said flange being adapted to lie flatwise against the inner surfaces of said upward projections, the latter serving as guides to facilitate the insertion of the tongues within the spaces aforesaid.

9. A carton made of a single blank adapted to be folded and secured together to produce a shell the bottom and side walls of which are of W-shape in vertical cross-section, a plurality of transverse members integrally secured at opposite upper corners thereof to the opposite upper edges of the side walls of the carton, said transverse partitions being adapted to be swung into vertically disposed substantially parallel relation for interlocking engagement with the longitudinally extending intermediate section of the carton, the side edges of said transverse partitions being so cut as to provide spaces between the upper portions thereof and the proximate side walls of the carton, and including a lid the free longitudinal edge of which is provided with a depending flange, said flange being provided with a plurality of tongues adapted respectively for reception within the spaces aforesaid whereby to detachably retain said lid in closed position.

10. A carton adapted to be folded and secured together to produce a shell having bottom and side walls, a plurality of transverse members integrally secured at opposite corners thereof to the opposite upper edges of the side walls of the carton, said transverse partitions being adapted to be swung into vertically disposed substantially parallel relation, means for retaining said transverse partitions in said last-mentioned relation, the side edge of at least one of said transverse partitions being so cut as to provide a space between the upper portion thereof and the proximate side wall of the carton, and a lid for the carton the free longitudinal edge of which is provided with a depending flange, said flange being provided with a tongue adapted for reception within the space aforesaid whereby to detachably retain said lid in closed position.

HENRY LEVINE.
